United States Patent Office

Des. 196,270
Patented Sept. 10, 1963

196,270

ILLUMINABLE MAGNIFIER UNIT

Jacob A. Mehr, Kirkwood, Mo., assignor to Dazor Manufacturing Corp., St. Louis, Mo., a corporation of Delaware

Filed Dec. 11, 1961, Ser. No. 67,847

Term of patent 14 years

(Cl. D57—1)

FIG. 1

FIG. 2

FIG. 1 is a top perspective view of an illuminable magnifier unit showing my new design, and

FIG. 2 is a bottom perspective view thereof.

The side not shown has substantially the same appearance as the side shown.

I claim:

The ornamental design for an illuminable magnifier unit, substantially as shown and described.
